UNITED STATES PATENT OFFICE.

FREDERICK H. CRAFTS, OF ROCHESTER, NEW YORK.

DESIGN FOR A TOOL FOR WORKING PLASTIC MATERIAL.

SPECIFICATION forming part of Design No. 26,830, dated March 30, 1897.

Application filed July 30, 1896. Serial No. 601,123. Term of patent 14 years.

To all whom it may concern:

Be it known that I, FREDERICK H. CRAFTS, of Rochester, in the county of Monroe, in the State of New York, have invented a new and useful Design for a Handle for Tools for Working Plastic Material, of which the following is a specification, reference being had to the accompanying drawings, showing a part thereof.

10 Figures 1 and 2 are respectively a top plan and a side elevation of a tool for working plastic materials embodying my invention.

The leading feature of my design consists in an elongated body, a substantially central longitudinal rib projecting downwardly from the bottom face of the body and having its opposite side faces inclined downwardly toward each other, and an arched or bow-shaped handle formed throughout its length

20 with transverse convolutions and having its opposite ends united to the opposite extremities of the top face of the body.

A represents the arched or bow-shaped handle, and a the transverse convolutions which are formed throughout the length of the handle and present the appearance of grooves in different planes. The opposite ends a' a' of the handle A are substantially parallel, and rise from the upper face of the

body B of a tool embodying my design. Said 30 body B is elongated and is arranged in a substantially horizontal plane directly beneath the handle A and substantially parallel and central therewith.

b represents the substantially longitudinal 35 rib which projects downwardly from the bottom face of the body B and is formed with opposite side faces inclined downwardly toward each other.

A tool embodying my design has a pleasing 40 and characteristic appearance, and is particularly applicable for use in the formation of cement and artificial stone walks and in the manipulation of plastic materials.

What I claim is—

45 The design for a tool for working plastic materials, substantially as shown and described.

In testimony whereof I have hereunto signed my name, in the presence of two attesting witnesses, at Rochester, in the county of Monroe, in the State of New York, this 18th day of July, 1896.

FREDERICK H. CRAFTS.
